UNITED STATES PATENT OFFICE.

GUS LINDAUER, OF PATCHOGUE, NEW YORK.

HOLDDOWN FOR SHIRTS.

Application filed April 4, 1924. Serial No. 704,162.

To all whom it may concern:

Be it known that I, GUS LINDAUER, a citizen of the United States of America, residing at Patchogue, in the county of Suffolk 5 and State of New York, have invented certain new and useful Improvements in Hold-downs for Shirts, of which the following is a specification.

This invention relates to hold-downs for 10 shirts and has particular reference to an elastic strap device associated with the tail portion of a man's shirt for properly holding the lower end of the shirt confined within the waist portion of trousers and preventing 15 upward creeping movement of the shirt to eliminate the sides of the shirt overhanging the waist band of the trousers.

A further object of the invention is to provide a strap device for holding down the 20 lower end of a shirt wherein a section of the strap extending between the legs has the opposite ends thereof detachably connected to a shirt adjacent its waist line and with the forwardly positioned strap portion 25 formed of detachably connected sections to permit removal of the strap from the crotch whenever desired.

With the above and other objects in view 30 that will become apparent as the nature of the invention is better understood, the same consists of the novel form, combination and arrangement of parts hereinafter more fully described, shown in the accompanying drawing and claimed.

In the drawing, wherein like reference 35 characters designate corresponding parts throughout the several views,

Figure 1 is a schematic view of the hold-down in its operative position and illustrated in front elevation,

Figure 2 is a similar rear elevational view of the hold-down,

Figure 3 is a developed plan view of the hold-down strap,

Figure 4 is a fragmentary edge elevational view of the front portion of the hold-down strap, and

Figure 5 is a fragmentary perspective view of the end of one of the front strap sections.

The hold-down is in the form of an elastic strap device embodying a fabric sheet or pad 1 substantially of triangular formation as illustrated in Fig. 3 having a front elastic strap 2 permanently attached to one corner thereof with the free end of the strap

2 folded upon itself as at 3 for reinforcing the strap and providing a substantial mounting for the keeper pin or hook 4 as shown in Figs. 4 and 5. A protecting or guard pad 60 5 is secured to the folded end 3 of the strap 2 and projects beyond the end of the strap as illustrated for purposes presently to appear.

A detachable elastic strap section 6 carries a loop keeper 7 at one end thereof for detachable engagement with the hook 4, the pad 5 underlying the keeper 7 and adjacent end of the strap section 6 to hold the same spaced from the body of the wearer. The 70 strap section 6 is looped as at 8 and is provided with the usual buckle 9 to facilitate lengthening and shortening thereof while a link 10 freely associated with the looped portion 8 carries a separable fastener 11 in 75 the form of a separable loop 12 and stud 13.

Each of the other corners of the triangular pad 1 carries an extensible elastic strap 14 provided with a separable clasp 15 at its outer terminal end, the strap section 2 being 80 positioned at the front side of the garment or person while the strap sections 14 are positioned rearwardly thereof.

In the use of the device, the separable 85 clasps 15 are attached to the shirt 8 adjacent each hip and the waist line as illustrated in Fig. 2 while adjustment of the strap sections positions the pad 1 adjacent the rear portion of the seat as illustrated. The strap 2 is passed between the legs and the separable clasp 12—13 is attached to the front side of the shirt adjacent the waist line as 90 shown in Fig. 1, adjustment of the strap sections 2 and 14 accommodating the hold-down device to persons of different sizes and proportions and effectively holding the lower end or tail portion of the shirt within the waist portion of the trousers to prevent upward creeping thereof. The clasp connection 4—7 is readily separable whenever desired to remove the strap 6 from the crotch, and the shirt may be removed from the body of the wearer with the separable parts of the hold-down attached thereto.

While there is herein shown and described the preferred embodiment of the present invention it is nevertheless to be understood that minor changes may be made therein without departing from the spirit and scope 100 of the invention as claimed.

What is claimed as new is:—

In a hold-down of the type described, a

triangular pad, a strap carried by one end portion thereof, a separable fastener carried by the free end of said strap, a protection pad projecting beyond the separable fastener, an adjustable strap having a separable fastener at one end to be connected to the first mentioned fastener and to overlie the protection pad, a separable garment fastening means carried by the free end of the adjustable strap, an adjustable strap carried by each of the remaining ends of the triangular pad, and a separable garment fastening means carried by the free end of each of the last-mentioned adjustable straps.

In testimony whereof I affix my signature.

GUS LINDAUER.
